BOTTLE HOLDER

James F. Buys, 4950 Marine Drive, Chicago 40, Ill.
Filed Mar. 27, 1958, Ser. No. 724,314
6 Claims. (Cl. 294—31.2)

My invention relates to bottle holders of the general class typified by U.S. Patent 2,160,662 issued May 30, 1939, to Tazewell H. Jenkins. It includes among its objects and advantages the adaptation of the holder of that patent to use on bottles that must go through an automatic washing machine with the holders in place on them.

In the accompanying drawings:

FIGURE 1 is a side elevation of the upper portion of the bottle with a holder according to the invention in place on it;

FIGURE 2 is a plan view of a holder according to the invention;

FIGURE 3 is a side elevation of the same holder with its parts in the positions occupied when carrying the bottle;

FIGURE 4 is a side elevation of the assembly eye before closure; and

FIGURE 5 is a side elevation of the same assembly eye after closure with the bail shown in full lines at the angular position occupied in one position of rest on the bottle and in dotted lines in the angular position for carrying.

The bottle 10 is of the configuration common for bottles having a capacity of one gallon, but equivalent bottles are made in half gallon sizes. The bottle has an upper bead 12 and a larger bead 14 axially spaced below the bead 12 and separated by a short neck 16. The bead 14 is commonly called the bumper roll.

The holder comprises the twin reaches 18 and 20 formed of a single piece of wire and integral with the lifting eye 22, which provides a fulcrum of limited flexibility between the reaches.

Opposite the eye 22 a companion eye is formed in two parts comprising a lower half eye 24 at the end of the reach 20 and an upper half eye 26 at the end of the reach 18. It will be noted that the reach 18 crosses above the reach 20 at both intersections, so that both lifting eyes are inclined downwardly and to the left, as indicated for the bifurcated lifting eye in FIGURES 1, 3, and 5.

The lifting handle comprises a straight cross bail 28, a first leg 30 extending down and articulated with the upper reach of the eye 22, and a second leg 32 reaching down and articulated with the lower half eye 24. This positions the articulations exactly opposite each other with respect to the center of the circle defined by the reaches 18 and 20 and with respect to the center of gravity when the article is being carried. It also makes the eyes available as stops to act in opposite senses in limiting the freedom of movement of the bail 28 and legs 30 and 32. The leg 32 is formed with an elbow at 34 and an end eye 36 turned counter-clockwise, as viewed in FIGURES 1, 3, 4, and 5. Thus, when the handle lies idle on the right side of the bottle, as indicated in full lines in FIGURE 1, the bight of the elbow 34 rides over the half eye 26, and with the leg eye 36 as high as it can go the bail 28 descends by gravity into contact, or substantially into contact, with the bottle.

It will be apparent that when the handle is thrown to the dotted line position of FIGURE 1, the articulation for the leg 32 exercises no restraint at all on the rotation of the handle. However, when the parts are moved to this position, which is the full line position of FIGURE 2, the leg eye 38 at the lower end of leg 30 will ride over the lower reach of the lifting eye 22 and function to restrain counter-clockwise rotation in precisely the same way. Be-

2

cause both lifting eyes slant downwardly and to the left as viewed in FIGURE 3, the elbow 40 in the leg 30 is materially shallower than the elbow 34 in the leg 32. In some instances, the shape and dimensions of the bottle may be such that the leg 30 can remain perfectly straight. The degree of angularity for both elbows 34 and 40 will vary with the relative diameters of the articulated eyes compared with the diameter of the wire itself.

It will be apparent from the foregoing that in the assembled structure the lifting eye 22 is a positive stop for arresting counter-clockwise rotation of the handle substantially at the point where the bail 28 strikes the bottle, and the other lifting eye 24, 26 is a positive stop limiting clockwise rotation at substantially the point where the bail 28 hits the bottle. Such limitation is quite immaterial, so far as the bottle itself is concerned, but this limitation accomplishes the novel function of making the device fool-proof with respect to being assembled on the bottle wrong side up by an unexperienced person.

As viewed in FIGURE 1, approximately the bottom 120° of a circle around the axis through the handle articulations is out of bounds for the handle movement. When correctly assembled, this is the space occupied by the bottle itself, but it is just as easy for an unexperienced operator to slip the ring down over the bottle neck the other side up and complete the assembly in that condition. But because of the obstruction, a person thus assembling it immediately finds that the bail 28 cannot rise more than about 30° above the horizontal, and this makes it impossible to pick up the bottle in a normal way and apprises the user that something is wrong before the user walks off, and a little yank unhooks the ring, and the bottle falls and is broken.

In assembly, the ring is positioned in the condition indicated in FIGURE 4 with the half eyes 24 and 26 disengaged from each other. The eye 24 has a bevelled end at 44, and these ends interlock, as indicated in FIGURE 5, and precisely as indicated in Jenkins Patent 2,160,662.

It will be noted that the wedging action disclosed in the Jenkins patent for springing the parts from the position of FIGURE 4 to the position of FIGURE 5 by swinging the handle is no longer available. The unexperienced person may, if he so desires, thrust a screw-driver along the line indicated at 46 in FIGURE 4, and then swing the handle of the screw-driver clockwise and engage the half eyes in the position of FIGURE 5. However, operators engaged in assembling such holders on the bottles, if the parts are properly proportioned, never find its necessary to use such a tool. With the reaches 18 and 20 bearing against the under surface of the bumper roll 18 a firm pressure with the finger tips on the reaches will move the half eye 24 from the position of FIGURE 4 over the top of the leg eye 36 far enough to let the half eye 26 slip up into place in the position of FIGURE 5.

It is emphasized that, as viewed in FIGURE 2, the right side of the eye 22, and the left half eye 24, are the portions directly articulated with the lower ends of the legs of the carrying handle. Thus, with respect to the vertical axis of the bottle, both load points are offset clockwise from the centers of the complete eyes 22, and 24—26, in the same clockwise sense. This is the exact reverse of the arrangement of FIGURE 3 of Jenkins Patent 2,160,662, where both legs are articulated with the lower halves of the complete lifting eyes and the load carrying the point on the left is offset counterclockwise from the center of the eye, but the load carrying contact on the right is offset clockwise.

Because of this reversal, the load points remain in a straight line passing through the bottle axis and the suspended bottle hangs vertical, rather than canted to one side.

A more significant functional result is that these iden-

tical load-carrying points, as viewed in FIGURES 1, 3, 4 and 5, obtain a radically different control of the rotation of the handle when the bottle is stationary and supporting the handle. The articulation with the half eye 24 is to the left of the center of the complete eye, so that the right half eye 26 limits clockwise rotation of the handle down from the lifting position of FIGURE 3 toward the bottle about the transverse horizontal line passing through both load carrying points. The articulation with the eye 22 is with the right side of that eye, so that the left side of the eye 22 limits counterclockwise rotation of the handle down toward the bottle from the lifting position of FIGURE 3. In other words, starting from the position of FIGURE 3, clockwise rotation of the handle is limited by the lifting eye nearest the observer approximately to a position resting by gravity on the right side of the bottle, while counterclockwise rotation is limited by the articulation farthest from the observer to the other position with the bail approximately in contact with the bottle on the left side. By the same token, if a hurried or careless operator slips the lifting loop into position on the bottle upside down with respect to the correct position of assembly, the first attempt to pick up the bottle reveals that the handle cannot move up farther than a point approximately 60° from the vertical position of FIGURE 3 and the error in assembly prevents any use at all and becomes immediately obvious.

From the foregoing, it will be apparent that I have accomplished at least the objects enumerated above, with the incidental minor advantage that the bottles will hang exactly vertical when picked up. This could be accomplished with a construction according to the patent only by making one of the reaches encircle more than 180° of the bottle neck, and the other reach less. Such asymmetry is a very difficult thing to achieve in mass production.

This application is a continuation in part of my pending application Serial Number 424,828 filed April 22, 1954, now abandoned.

Others may readily adapt the invention for use under various conditions of service by employing one or more of the novel features disclosed or equivalents thereof. As at present advised, with respect to the apparent scope of my invention, I desire to claim the following subject matter:

1. In a carrying bottle holder of the type comprising ring means adapted to encircle a flanged bottle neck below the flange; and U-shaped handle means, comprising a carrying bail and legs extending down to engage said ring means; the combination of opposite arcuate reaches each shaped to encircle substantially half said neck; said reaches, jointly, constituting said ring means; a first, permanent, ring connection between the adjacent ends of said reaches on one side of said neck; a first, permanent,

interlocking, articulated leg connection between said ring and one of said legs; said first, articulated leg connection being at said first ring connection; a second ring connection between said reaches at their remote ends on the opposite side of said neck; said second ring connection being detachable to permit assembly with a bottle; and a second, articulated leg connection between the other of said legs and said reaches; said second, articulated leg connection being at said second ring connection; the ends 10 of said reaches at said ring connections having portions projecting into the paths of the adjacent ends of said handle legs to prevent rotation of said handle into a position extending downward when said reaches are on a bottle right side up; whereby assembling the reaches wrong side up prevents the bail from extending upward and thus compels the operator to reverse the reaches into the right side up position.

2. A combination according to claim 1, in which said second reach connection comprises reversely turned end portions having beveled ends adapted to slip past each other into interlocking engagement.

3. A combination according to claim 2, in which said ring is of larger diameter in unassembled, undistorted condition, than in assembled, locked condition.

25 4. A combination according to claim 3, in which said reaches cross each other adjacent the second reach connection, and said reversely turned portions are beyond the crossing; the beveled ends tending to press the crossed reaches against each other; whereby abutment of the crossed reaches holds the beveled ends in locked abutment.

30 5. A combination according to claim 4 in which said reaches in undistorted condition hold said separable connection separate, and define an opening large enough to pass over a bead on the neck of the bottle to be carried; said reaches being adapted to yield resiliently under the pressure of the finger tips of a user, and permit said connection to snap into locked position; said reaches and handle being of wire of circular cross-section, and said first, permanent connection being a lifting eye integral with said reaches.

35 6. A combination according to claim 5 in which said separable connection is a bifurcated lifting eye, each half of said eye being integral with one of said reaches; said reaches crossing each other, one above the other, where they merge into said separable connection; said second articulated leg connection being articulated with the underlying half eye.
